(57) CLAIM

The ornamental design for a bag, as shown and described.

DESCRIPTION

FIG. 1 is front view of a bag according to the present invention;

FIG. 2 is front view of the bag depicted in FIG. 1 with the lower left corner cut away so that a fluid contained in the bag is removed therefrom according to the present invention; FIG. 3 is a right side view of the bag depicted in FIG. 1 (the left side being a mirror image thereof);

FIG. 4 is a top view of the bag depicted in FIG. 1;

FIG. 5 is a top and rear perspective view of the bag depicted in FIG. 1; and,

FIG. 6 is a bottom view of the bag depicted in FIG. 1.

The stippling in the figures represent areas where the transparent container walls of the bag are joined together and produce a translucent area.
